Primary Examiner — Jonathan J Han(74) *Attorney, Agent, or Firm* — Schwabe, Williamson & Wyatt, P.C.(57) **CLAIM**

We claim the ornamental design for footwear, as shown and described.

DESCRIPTION

FIG. 1 is a front perspective view of footwear, showing our new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The dot-dash broken lines adjacent to the shaded area represent unclaimed boundaries of the claimed design and which form no part thereof. The remainder of the broken lines show elements of the footwear that form no part of the claimed design.
